UNITED STATES PATENT OFFICE

134,138

DESIGN FOR A BUCKLE

Clarence M. Smith, Naugatuck, Conn., assignor
to Parva Products Company, Chicago, Ill., a
corporation of Delaware

Application August 13, 1942, Serial No. 107,929

Term of patent 14 years

To all whom it may concern:

Be it known that I, Clarence M. Smith, a citizen of the United States, residing at Naugatuck, in the county of New Haven and State of Connecticut, have invented a new, original, and ornamental Design for a Buckle, of which the following is a specification, reference being had to the accompanying drawing forming a part thereof.

Fig. 1 is a top plan view of a buckle embodying my new design;

Fig. 2 is a side elevational view of the buckle shown in Fig. 1;

Fig. 3 is a perspective view of the buckle of Figs. 1 and 2; and

Fig. 4 is a similar perspective view taken from the opposite end of the buckle.

The characterizing features of my new design reside in the configuration of the buckle frame as shown in full lines.

I claim:

The ornamental design for a buckle, substantially as shown and described.

CLARENCE M. SMITH.
